Atty.

UNITED STATES PATENT OFFICE.

SAMUEL HEATH, OF PHILADELPHIA, PENNSYLVANIA.

COMBINATION-BRACKET FOR SCREENS, SHADES, AND CURTAINS.

1,337,768.

Specification of Letters Patent. Patented Apr. 20, 1920.

Application filed April 16, 1919. Serial No. 290,517.

To all whom it may concern:

Be it known that I, SAMUEL HEATH, a citizen of the United States, residing at Philadelphia, in the county of Philadelphia and State of Pennsylvania, have invented new and useful Improvements in Combination-Brackets for Screens, Shades, and Curtains, of which the following is a specification.

10 My invention relates to a new and useful improvement in combination bracket for screens, shades and curtains, and has for its object to provide an exceedingly simple and effective bracket so formed as to be reversible and capable of supporting at one and the same time a rolling screen, a shade and a curtain.

With these ends in view, my invention consists in the details of construction and 20 combination of elements, hereinafter set forth and then specifically designated by the claims.

In order that those skilled in the art to which this invention appertains, may understand how to make and use the same, I 25 will describe its construction in detail referring by numerals to the accompanying drawing forming a part of this application, in which:—

30 Figure 1, is a side elevation of a bracket made in accordance with my improvement.

Fig. 2, is an edge view thereof looking downward showing the bracket applied to a window frame, and

35 Fig. 3, is an end view thereof.

In carrying out my invention as here embodied the bracket is formed from a single piece of wire so bent as to produce attaching eyes 1, and the base members 2 from which 40 latter extend the reach members 3 at right angles to the base members. With these members are formed the loops 4 one extending upward and the other downward and with the lower member is also formed a loop 45 5, while with the upper member is formed a double loop 6.

The loops 4 serve as sockets for the support of one of the pintles for a shade roll and the loop 5 also serves as a socket for the 50 pinte of a shade roll, while the loop 6 serves as a socket for the pinte of a spring roll for a rolling screen when the bracket is set in one position upon a window frame or it is intended to serve as a socket for the support 55 of a curtain rod when set in the position upon the window frame.

The reach members 3 are offset as shown at 7 in order to bring the loop 6 relatively close to the window frame so that the rolling screen may as nearly as possible fill the 60 whole space between the sides of the window frame.

When a bracket is to be used for supporting two shades and a curtain it is secured to the face of the window frame so that it will 65 project out into the room or in the reversed direction from that shown in Fig. 2. A white shade may be supported by the loop 4, while a dark shade is supported by the loop 5 and the curtain rod by the loop 6, 70 thus providing for the complete equipment of a window.

Where only a single shade is to be hung the bracket may be turned upside down from the position shown in Fig. 1 and the 75 upper loop 4 will then become the lower loop and may be utilized as the socket for the pinte of the shade roll.

If desired my improved bracket can be made from sheet metal or cast, but of course 80 I do not wish to be limited to the exact details of construction as herein shown as these may be varied within the limits of the appended claims without departing from the spirit of my invention. 85

Having thus fully described my invention, what I claim as new and useful is:—

1. In a bracket of the character described, attaching loops, base members, reach members standing at right angles to said base 90 members, an upper and lower loop formed in the reach members, an offset formed in the reach members, and two additional loops formed in the outer portion of said reach members beyond the offset 3. 95

2. A combination bracket comprising base members provided with attaching loops, reach members projecting at right angles to said base members, oppositely projecting loops carried by said reach members, inwardly projecting offsets in said reach members, another loop formed from one of the reach members, beyond the oppositely projecting loops and a double loop projecting opposite the last named loop beyond the latter and adjacent the outer end of the reach members. 105

In testimony whereof, I have hereunto affixed my signature.

SAMUEL HEATH.
